US00D815728S

(12) **United States Design Patent** (10) **Patent No.:** **US D815,728 S**
(45) **Date of Patent:** **** Apr. 17, 2018**

(54) **BREATHING INTERFACE ASSEMBLY**

(71) Applicant: **Fisher & Paykel Healthcare Limited**,
Auckland (NZ)

(72) Inventors: **Bruce Michael Walls**, Auckland (NZ);
Rex Gordon Faithfull, Auckland (NZ);
Arvin San Jose Gardiola, Auckland (NZ);
Wen Dong Huang, Auckland (NZ);
Matthew Robert Geoff Slight,
Auckland (NZ)

(73) Assignee: **Fisher & Paykel Healthcare Limited**,
Auckland (NZ)

(**) Term: **15 Years**

(21) Appl. No.: **29/581,677**

(22) Filed: **Oct. 20, 2016**

Related U.S. Application Data

(62) Division of application No. 29/475,080, filed on Nov. 27, 2013, now Pat. No. Des. 770,036.

(51) **LOC (11) Cl.** **29-02**

(57) **CLAIM**

The ornamental design for a breathing interface assembly, as shown and described.

DESCRIPTION

FIG. 1 is a top, front and right side perspective view of a breathing interface assembly embodying the new design.

FIG. 2 is a front view thereof.

FIG. 3 is a back view thereof.

FIG. 4 is a left side view thereof.

FIG. 5 is a right side view thereof.

FIG. 6 is a top view thereof; and,

FIG. 7 is a bottom view thereof.

Broken lines are used to illustrate features that form no part of the claimed design.

1 Claim, 7 Drawing Sheets
